UNITED STATES PATENT OFFICE

106,851

DESIGN FOR A DRESS

Philip Schlessel, New York, N. Y.

Application October 1, 1937, Serial No. 71,907

Term of patent 3½ years

To all whom it may concern:

Be it known that I, Philip Schlessel, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein

The grouped floral units on the bust portion of the dress comprise a superimposed pocket, as shown.

I claim:

The ornamental design for a dress, substantially as shown and described.

PHILIP SCHLESSEL.
